ATTORNEY

UNITED STATES PATENT OFFICE.

WALTER J. PASINSKI, OF DETROIT, MICHIGAN, ASSIGNOR TO BURROUGHS ADDING MACHINE COMPANY, OF DETROIT, MICHIGAN, A CORPORATION OF MICHIGAN.

RECORDING MECHANISM.

Application filed May 1, 1924. Serial No. 710,208.

To all whom it may concern:

Be it known that I, WALTER J. PASINSKI, a citizen of the United States, residing at Detroit, in the county of Wayne and State 5 of Michigan, have invented certain new and useful Improvements in Recording Mechanism, of which the following is a specification.

This invention relates to recording mechanisms of adding and listing machines and the like, and more particularly to that type 10 of machine in which the several type of each denominational series are adapted to be independently moved or driven against the 15 paper on the platen by the action of a hammer.

The object of my invention is to provide an improved device for yieldingly retracting the type. It is common to retract or restore 20 the type by spring action after the type have been struck by the hammer and driven against the platen, the action being a percussive one. Heretofore various forms of 25 devices have been suggested for performing this function, as, for example, single springs for the individual type, spring-actuated levers having fixed pivots or hinge-connections which are subject to wear, or a plurality 30 of leaf springs hinged at one end and subject to rapid crystallization and wear.

More specifically, the principal object of my invention is to provide a type restoring device which is simple and cheap in construction, formed of a minimum number of 35 parts, easily and quickly assembled and inspected, and subject to minimum wear and deterioration, and yet effective in operation.

The accompanying drawings, which form part of this specification, illustrate a preferred form of embodiment of my invention, and I have shown for purposes of illustration my invention applied to the well known Moon-Hopkins billing machine, although it is to be understood that the use 45 of my invention is not limited thereto as it is equally applicable to other kinds of listing or recording machines.

Of said drawings, Fig. 1 is a fragmentary view, partly in section, taken alongside of 50 one of the rack and type bars of a Moon-Hopkins machine, showing my invention applied thereto; Figs. 2 and 3 are similar

sectional elevations of a type bar and its type, the section being taken along one side of the type, as on the line 2—2 of Fig. 4, 55 with Fig. 2 showing the parts in normal condition and Fig. 3 showing the parts in the condition which they assume when the "8" type is projected against the platen by the hammer; Fig. 4 is a vertical section 60 taken on the line 4—4 of Fig. 2, and Fig. 5 is a vertical section taken on the line 5—5 of Fig. 2.

It is unnecessary to describe in detail the machine proper as it is one well known on the market and well disclosed in various 65 patents. In general, the racks 6 carry and are integral with the type bars 7 on each of which are mounted a denominational series of type pieces 8. During the operation 70 of the machine and after the type bars have been differentially positioned, a universal bar 9 is lowered to trip latches 10 and then studs 11 on firing latches 12 act on the tails of hammers 13, to project the striking 75 noses 14 of the hammers against the type pieces on the printing line to drive such type pieces upwardly against the paper on platen 15.

The type of each series are vertically slidably mounted in a housing, one side of which is formed by the type bar 7 and the other side by a plate 16 having inwardly directed flanges 17 along its upper and lower edges. These flanges 17 are provided with 80 slots or grooves 18, in which the type 8 are vertically slidable. The plate 16 is secured 85 to the type bar 7 by rivets 19. There are ten type to each denominational series and as usual, the faces of their heads are embossed from "0" to "9." 90

Each type has a shoulder or projection 21 intermediate its ends, extending into the recess or groove 22 formed by and between the flanges 17 of the plate 16. Supported on 95 these projections 21 is a universal bar 23 which has downwardly-depending triangular-shaped fingers 24 extending between the projections 21 on the type. A leaf spring 20, formed as shown in Figs. 2 and 3, has 100 its ends resting on the upper edge of the universal bar 23 and its central portion has a curved hump or bend 25 which seats in a correspondingly curved recess formed in the

lower edge of the upper flange 17 of the plate 16. Each end of the universal bar 23 is provided with a vertical projection 26.

- The spring 20 is under compression between its central portion and its ends so that the universal bar is yieldingly pressed against the projections 21 on the type. When one of the type is struck by the hammer, for example, the "8" type as shown in Fig. 3, the universal bar 23 is raised and the spring 20 yields, its tension being increased, so that when the hammer 13 drops the operated type is retracted to normal position by the universal bar 23 and spring 20. It will be noted that when the "8" or "9" type is operated, the universal bar 23 will rock about the projection 21 on the "0" type as a fulcrum and when the "0" or "1" type is operated, the universal bar will rock about the projection 21 of the "9" type as a fulcrum. When one of the other or intermediate type is operated, the end of the universal bar, which is nearer the type, will be elevated until the projection 26 on such end engages the underside of the upper flange 17 and then the bar will fulcrum about that end and its other end will be raised an extent dependent upon the distance of the operated type from the center of the spring 20. The lower ends of the type are provided with shoulders 27 which are adapted to positively limit the throw of the type by striking against the lower edge of the type bar 7 and plate 16, and form a broad striking face for the hammers.

When the universal bar 23 is raised by one of the type, other than the "0" or "9" type, it is prevented from being accidentally laterally displaced in both directions by the fingers 24 on the opposite sides of the shoulder 21 of the operated type. When the "0" or "9" type is operated, the finger 24 on the inner side of its shoulder 21 prevents lateral movement of the universal bar 23 in one direction and the finger 24 on the inner side of the shoulder 21 of the other end type, on which the bar fulcrums, prevents lateral displacement of the latter in the opposite direction. The central curved bend 25 on the spring 20, through its engagement in its recess, properly centers the spring with respect to the type, and this recess together with the projections 26 on the ends of the bar 23 prevent lateral displacement of the spring.

From the above description, it will be obvious that the device, embodying my invention, is very simple in design, as it consists essentially of a universal bar and a single leaf spring neither of which are hinged or fixedly pivoted, nor subject to excessive wear, while at the same time they may be readily assembled or replaced and are admirably adapted to effectively perform the functions for which they are de-

signed. The spring acts with substantial uniformity upon each one of the type of the series.

I claim:

1. In recording mechanism, the combination of a housing, a series of type slidably mounted therein, a universal bar engaging said type to retract them, and a spring mounted in said housing and engaging said bar to normally hold the latter against the several type of the series.

2. In recording mechanism, the combination of a housing, a series of type slidably mounted therein, a universal bar engaging said type, and a leaf spring engaging said bar to normally hold it against the several type of the series and retract the operated type.

3. In recording mechanism, the combination of a housing, a series of type slidably mounted therein, a universal bar for retracting the several type of the series, and a leaf spring having its end portions engaging said bar and a central seated portion.

4. In recording mechanism, the combination of a housing, a series of type slidably mounted therein, a universal bar mounted within said housing for retracting the several type of the series, and a leaf spring mounted in said housing and compressed between the housing and said bar, with its end portions engaging said bar and its central portion engaging said housing.

5. In recording mechanism, the combination of a housing, a series of type slidably mounted therein, a universal bar for retracting the several type of the series, and a leaf spring having its central portion formed to seat in a recess and its end portions pressing against the ends of said bar.

6. In recording mechanism, the combination of a housing, a series of type slidably mounted therein, a universal bar engaging said type and having fingers extending between the type to prevent displacement of the bar, and a leaf spring engaging said bar to normally hold it against the type and retract the operated type.

7. In recording mechanism, the combination of a housing, a series of type slidably mounted therein, a universal bar engaging said type and having fingers extending between the type to prevent displacement of the bar and a leaf spring mounted in said housing and having a central portion formed to seat in a recess with its ends pressing against the ends of the universal bar to normally hold the latter against the type and retract the operated type.

8. In recording mechanism, the combination of a housing, a series of type slidably mounted therein, a universal bar engaging said type and having fingers extending between the type to prevent displacement of the bar, a leaf spring acting on the bar to

normally hold it against the type and retract the operated type and projections on the end of said bar to prevent displacement of said spring.

5. In recording mechanism, the combination of a housing, a series of type slidably mounted therein, a universal bar engaging said type and having fingers extending be-

tween the type to prevent displacement of the bar, a leaf spring having its central portion formed to seat in a recess with its ends resting on said bar, and projections on the end of said bar for preventing displacement of said spring. 10

WALTER J. PASINSKI.
